UNITED STATES PATENT OFFICE.

URIAH TIMOTHY E. HALLMAN, OF TORONTO, ONTARIO, CANADA, ASSIGNOR OF ONE-HALF TO HARRY P. LANG, OF TORONTO, ONTARIO, CANADA.

CHANGE-SPEED MECHANISM FOR AUTOMOBILES.

Application filed May 9, 1919. Serial No. 295,896.

To all whom it may concern:

Be it known that I, URIAH TIMOTHY E. HALLMAN, of the city of Toronto, in the county of York, in the Province of Ontario, Canada, have invented certain new and useful Improvements in Change-Speed Mechanisms for Automobiles, of which the following is the specification.

My invention relates to improvements in change speed mechanisms for automobiles and the object of the invention is to devise a device which will be simple, quick and easy of manipulation, in which the torque remains constant during operation of changing speed, in which any desired speed may be produced from maximum to zero, in which the reversing operation is performed without throwing any gear out of mesh, in which all danger of gear stripping is avoided and in which the change speed and reversing mechanism are operated by a single lever and it consists of the arrangement and construction of parts as hereinafter more particularly explained.

Fig. 1, is a side elevation of my device showing its location in the automobile body and its connection to the engine.

Fig. 2, is a plan view of the parts shown in Fig. 1.

Fig. 3, is a longitudinal section through the outer casing of my device showing the interior mechanism in full.

Fig. 4, is an enlarged sectional detail through the left hand portion of my mechanism.

Fig. 5, is a similar view to Fig. 4 through the right hand portion of my mechanism and being a continuation of the parts shown in Fig. 4.

Fig. 6, is a cross sectional view on line $x-y$ Fig. 4.

Fig. 7, is a cross sectional view on line $x'-y'$ Fig. 5, showing the piston heads in full.

Fig. 8, is a detail view partially in section of the main cam and adjacent mechanism co-acting therewith.

Fig. 9, is a perspective detail of one end of one of the cylindrical controlling valves.

Fig. 10, is an enlarged perspective detail of the clutch sleeve operating my change speed mechanism.

Fig. 11, is a perspective detail of the bearing sleeve employed in my change speed mechanism.

Fig. 12, is a side elevation of the sleeve shown in Fig. 10 mounted upon its supporting shaft and the lugs of the sleeve shown in Fig. 11 shown in their position in section.

Fig. 13, is a sectional view on line x^2-y^2 Fig. 12.

Fig. 14, is a perspective detail of the foot plate co-acting with the foot lever controlling my mechanism.

Fig. 15, is an enlarged sectional detail of one of the main bearings of my device.

Fig. 16, is a sectional detail of the sleeve and adjacent parts.

In the drawings like characters of reference indicate corresponding parts in the various figures.

1 indicates the floor of an automobile which is provided with a foot board 1^x having a slotted orifice 1° through which the operating lever hereinafter described extends. 2 indicates a portion of the automobile engine provided with the usual body 2^x in which is journaled the engine shaft 2°. 2' indicates an arm which extends rearwardly from the side of the body 2^x adjacent to the engine shaft bearing. The engine shaft 2° is provided with a head 2² which is circular in form. 3 indicates a fly wheel provided with a circular recess 3^x into which the head 2² fits and a central orifice 3° concentric with the recess 3^x. 3' indicates a plate provided with a circular projection 3² which fits in the orifice 3° and 3³ indicate bolts which extend through the head 2², fly wheel 3 and plate 3' securing the parts together.

3⁴ indicates a pin which extends radially from the plate 3' which revolves in unison with the fly wheel and which practically is an integral part thereof.

4 and 4^x indicate the longitudinal bars forming the main frame of the chassis of the automobile. 4° indicates a cross bar con-

necting such bars 4 and 4^x together, the bar 4° being provided intermediately of its length with a bearing portion 4' provided with a covering cap 4². 5 indicates a cylinder which forms the main casing of my device. The cylinder 5 is provided with heads 6 and 7°. The head 6 is provided with a central recess 6^x in which fits the circular plate 3'. The wall of the 10 recess 6^x is provided with a radial notch 6° into which the pin 3⁴ extends. The head 6 is also provided with a longitudinally extending central orifice 6' having an enlarged outer end 6² for a purpose which will hereinafter appear. The orifice 6' proper is provided at its ends with annular recessed portions 6³ and 6⁴ in which fit bearing cups 6⁵ and 6⁶ and a suitable packing 6⁵. 6⁷ indicates an orifice formed in the head 6 and 15 extending radially from the orifice enlargement 6². The inner portion of the head 6 is cored out into an annular chamber 6⁸ formed concentrically with the orifice 6'. 6⁹ indicates an orifice formed in the head 6 to the inside of the orifice 6⁷. The upper portion of the orifice 6⁹ is provided with an internally threaded portion 6¹⁰, the lower portion of the orifice being enlarged into a chamber 6¹¹ from which extends a reduced 20 orifice 6¹², the upper portion of which is provided with a tapered valve seat. 6¹³ indicates a passage connecting the orifice 6⁷ with the lower end of the orifice 6¹². 6¹⁴ indicates a passage connecting the chamber 6¹¹ 25 with the annularly cored chamber 6⁸. 6¹⁵ indicate orifices extending through the inner wall of the cored chamber 6⁸ for a purpose which will hereinafter appear. The inner end of the head 6 is provided with a rabbet groove 6¹⁶. The inner face of the 30 head 6 is provided with a series of recesses 6¹⁷ arranged concentrically around the centre of the head.

7 indicates the main or power transmission shaft of my device which is provided at one end with bearing cones 7^x and 7° opposing the cups 6⁴ and 6⁵ hereinbefore described and between which are located the balls 7' and 7²⁰. By this means the main 40 cylinder 5 is rotatably mounted at one end upon the corresponding end of the shaft 7. The head 7° of the casing 5 is provided with a central orifice 7^{o2} in which is located a peculiarly constructed bushing by which the 45 cylinder 5 is supported upon the shaft 7 and which I will later describe.

The shaft 7 protrudes from the end of the casing 5 past the head 7° and is provided with a series of longitudinally extending 50 splines 7² and 7³ indicates a short shaft which is located in axial alignment with the shaft 7. The shaft 7³ is mounted in a stationary bearing sleeve 7⁴ which is secured in the bearing recess 4' and cap 4², the shaft 7³ being supported within the sleeve 7⁴ by means

of ball bearings 7⁵. The shaft 7³ is also provided with a longitudinally extending orifice 7⁶ into which the reduced portion 7⁷ of the main shaft 7 freely extends thereby supporting the opposite end of the main 70 shaft. Intermediately between that portion of the shaft 7 carrying the splines 7² and the reduced portion 7⁷ is located a sided portion 7⁸ and a threaded portion 7⁹. Upon the sided portion 7⁸ is mounted a clutch member 8, which is secured in place by a nut 8⁰ screwed upon the portion 7⁹ against the outer side of the clutch member 8. 75

10 indicates the transmission shaft of the automobile which is connected to the end of the shaft 7⁸ by a universal joint connection 80 10⁰, which is of ordinary construction and is, therefore, not shown in detail.

5⁰ indicate a series of bosses, which are formed within the casing 5 and to which 85 are secured guide bars 9 secured to the bosses 5⁰ by tap screws 5¹. The guide bars 9 are provided with oppositely directed guiding faces 9^x and 9° and bolt ends 9' and 9². The bolt end 9' is provided with a nut 9³ and 90 the end 9² with a nut 9⁴ serving to tie the heads 6 and 7^{o1} together.

11, 11⁰, 11^x, 11¹ and 11² indicate a series 95 of cylindrical valves located at one end of the main casing 5. The cylindrical valves 11, 11⁰, 11^x, 11¹ and 11² are provided at their ends with annular flanges 11³ and 11⁴. At the outside of the annular flange 11³ each cylindrical valve is provided with an annular tapered seating portion 11⁵ co-acting with 100 the valve seat 11⁶, which is secured within the recess 6¹⁷ of the head 6. The flange 11³ of each cylindrical valve is provided with a segmental shaped recess 11⁷ as clearly shown in Fig. 9. 105

12, 12⁰, 12^x, 12¹ and 12² indicate cylindrical valves similar to the valves 11, 11⁰, 11^x, 11¹ and 11², the cylindrical valves 12 to 12² being located in the opposite end of the cylinder 5 and are provided with annular 110 flanges 12³ and 12⁴ and annular seating portions 12⁵ co-acting with the valve seats 12⁶ located in the head 7^{o1}. The annular flanges 12⁴ are also provided with segmental recesses 12⁷ similar to the recesses 11⁷. 115

It will be noticed that the cylindrical valves 11 to 11² and 12 to 12² are arranged concentrically around the main shaft 7.

13 and 14 indicate sleeves mounted upon the shaft 7, the sleeve 13 being for the major 120 portion located centrally within the series of cylindrical valves 11 to 11² and the sleeve 14 centrally within the series of cylindrical valves 12 to 12². The sleeve 13 is provided at its outer end with a threaded portion 13^x 125 terminating in an annular shoulder 13°. Upon the threaded portion 13^x is screwed an annular member 13¹ provided with an annular flange 13² which fits into the segmental recesses 11⁷ of the cylindrical valves 11 to 130

11². In proximity to the opposite end of the sleeve 13 is located an annular flange 13³ which is held in contact with the outer face of the flange 11⁴ of each of the cylindrical valves 11 to 11². The extreme inner end of the sleeve 13 is provided with an internal recess 13⁴, which extends concentrically around the shaft 7 and at its extreme end with an annular flange 13⁵. The sleeve 14 is provided with an externally threaded portion 14^x terminating at its inner end in a shoulder 14⁰. 14' indicates an annular member similar to the member 13', the member 14' being provided with an annular flange 14² which passes through the segmental recesses 12⁷ of the cylindrical valves 12 to 12². The opposite end of the sleeve 14 is provided with an annular flange 14³ bearing against the annular flanges 12⁴ of the cylinders 12 to 12². The inner end of the sleeve 14 is also provided with an internal recess 14⁴ and at its extreme end with an external annular flange 14⁵. By this construction it will be seen that the cylindrical valves 11 to 11² are tied to the sleeve 13 so that when the sleeve 13 moves longitudinally upon the shaft 7 all the cylindrical valves 11 to 11² move therewith. Similarly all the cylindrical valves 12 to 12² are tied to the sleeve 14 so that when the sleeve 14 moves longitudinally upon the shaft 7 all the valves 12 to 12² move therewith.

15 indicates a cylindrical cam, which is secured by cotter pins 15⁰ to the shaft 7 and is provided with an inclined groove 15^x which encircles the same. The cam 15 is provided at its ends with recesses 15' and 15². 16 indicates a spring which fits into the recesses 14⁴ and 15'. 17 indicates a spring which fits into the recesses 15² and 13⁴. The tendency of the springs 16 and 17 is to force the sleeves 13 and 14 outwardly from the cam 15.

I will now describe the mechanism by which the cylindrical valves 11 to 11² and 12 to 12² are controlled by the driver of the car.

18 indicates a shaft, which extends across the frame of the chassis and is journaled at its ends in brackets carried by the side bars 4 and 4^x. 19 indicates a casting, which is secured to the arm 2' of the engine. 19^x indicates a bearing sleeve which extends from the casting 19 and in which is journaled a shaft 20. The shaft 20 is provided at its ends with flattened faces 20^x and 20⁰.

21 indicates a lever arm provided at its lower end with a jaw 21^x extending against each flattened portion 20^x and 20⁰, the jaws being circular in form and connected to the shaft by a pin 21' extending through the jaws and through the shaft 20. By this means the lever arm is pivotally swung to move in a backward and forward direction with the shaft 20 and in a lateral direction

upon the pin 21'. 22 indicates a push rod which is secured at one end in the upper end of the lever arm 21 and extends at its opposite end through the slot 1⁰ of the foot board of the car and is provided with a broad U-shape pedal 23 in which the foot of the operator is designed to fit. The lever arm 21 is connected by a tension spring 21² to the foot board of the car. The opposite end of the shaft 20 is provided with 75 an arm 24 which is preferably jaw shape.

25 indicates a rod provided at one end with a flattened portion 25^x fitting within the jaw 24 and at the opposite end with a flattened portion 25⁰ which is pivotally 80 connected by a pin 25' to a lever arm 25² secured upon the cross shaft 18. 26 indicates a clutch sleeve provided with three splines 26^x, 26⁰ and 26'.

On referring to Fig. 13 it will be seen 85 that the shaft 7 is provided with six splines 7² and that the splines 26^x, 26⁰ and 26' fit into each alternate groove formed by the splines 7².

18^x indicates a fork, which is carried by 90 the cross shaft 18 and engages the annular groove 26² of the clutch sleeve 26. 7¹⁰ indicates a bushing sleeve which fits in the bearing orifice 7⁰². 7¹¹ indicates a bushing sleeve fitting within the sleeve 7¹⁰. The bushing 95 sleeve 7¹⁰ is provided with an enlarged inner end 7¹² fitting in a corresponding recess formed in the head 7⁰¹. The corresponding end of the bushing sleeve 7¹¹ is also provided with an enlargement 7¹³ bearing against the 100 outer end of the enlargement 7¹². The opposite end of the bushing sleeve 7¹¹ is provided with a threaded portion 7¹⁴ upon which is threaded a union nut 7¹⁵ extending over the outer end of the bushing sleeve 7¹⁰ 105 and provided with suitable packing 7¹⁶. The outer end of the sleeve 7¹¹ is provided with internal splines 7¹⁷, 7¹⁸ and 7¹⁹ which fit into remaining grooves formed between the splines 7². 7²⁰, 7²¹ and 7²² indicate a series of packing rings extending around the 110 shaft 7 at the end of the sleeve 14.

It will be noted on referring to Fig. 5 that the end of the sleeve 14 extends into the bushing sleeve 7¹¹ and that the rings 115 7²⁰, 7²¹ and 7²² bear against the end of the sleeve 14 and are provided with interposed packing rings 7²³ and 7²⁴ and triangular rings 7²⁵ located between each of the rings 7²⁰, 7²¹ and 7²² so as to make an air tight 120 joint (see Fig. 15).

27 indicates a plate provided with notches which co-act with the lever arm 21. The plate 27 is provided with a central notch 27^x in which the lever 21 is located when the 125 parts are in their neutral position and with the notch 27⁰ into which the lever 21 is moved when a forward drive is required and notch 27' when the reverse drive is required. When moving the lever 21 from the notch 130

27^x into the notch 27° the spring 21² draws the lever 21 upwardly into the notch 27° thereby turning the shaft 20 in a corresponding direction and carrying the arm 24 in the same direction. By this construction the rod 25 is carried in the direction of arrow, swinging the lever arm 25² in the same direction so as to rock the shaft 18 in the direction of arrow (see Fig. 2) and 10 carrying the fork 18^x in a corresponding direction, and withdrawing the clutch sleeve 26. By this construction the splines 26^x, 26° and 26² are carried away from the end of the sleeve 14, releasing such sleeve and allowing 15 the spring 16 to act to carry the sleeve longitudinally in the direction of arrow (see Fig. 3) and thereby carrying the cylindrical valves 12 to 12² to their seating position.

In order to carry the valves 11 to 11² also 20 to their seating position simultaneously with the cylindrical valves 12 to 12² I have provided the following mechanism.

15³ indicate a series of bores extending longitudinally through the cam 15. 28 indicate rods which are slidably held in the bores 15³ and secured at their outer ends in the annular flange 14⁵. 15⁴ indicate a series of bores also extending through the cam 15 and 29 indicate rods slidably held within the 30 bores 15⁴ and secured at their outer ends in the annular flange 13⁵.

It will be noticed on referring to Fig. 6 that the rods 28 and 29 are arranged in pairs. 15⁵ indicates a recess formed in the end of 35 the cam 15 and connecting each pair of bores 15³ and 15⁴ together. In proximity to the ends of each of the rods 28 and 29 are formed slots 28^x and 29^x. 30 indicate levers pivotally mounted in the recesses 15⁵ by pins 30^x. 40 The lever 30 is provided with rounded ends fitting into the slots 28^x and 29^x. It will thus be seen that when the rod 28 is moved in one direction the rod 29 will be moved in the opposite direction and, therefore, when the 45 sleeve 14 is released by the clutch sleeve 26 as above described and moves outwardly in the direction of arrow (see Fig. 3) the sleeve 13 moves in an opposite direction to the direction of arrow (see Fig. 3) through the 50 action of the rods 28 and 29 connected to the flanges 13⁵ and 14⁵ of the sleeves 13 and 14 and the levers 30.

It will thus be seen by the operation of the lever 21 above described that the cylindrical valves 11 to 11² and 12 to 12² will be simultaneously carried outward towards their seats 11⁶ and 12⁶.

31 indicates a piston. A piston 31 fits in each cylinder 11 to 11² and co-acts therewith. 60 32 indicates a similar piston which fits in each cylindrical valve 12 to 12² to co-act therewith. The pistons 31 and 32 are preferably formed with a tapered recess 31^x and a central orifice 31' extending through 65 the head of the piston. 33 indicates a pis-

ton rod, a piston rod 33 connecting each pair of pistons 31 and 32. Each end of the piston rod 33 is provided with a tapered head 33^x fitting the tapered recess 31^x. 34¹⁰ indicates a screw extending through the orifice 31' into the end of the piston rod 33 to connect the piston and piston rod together. The sides of the piston rod are provided with slides 34 and 35 slideable upon the faces 9^x and 9° of the guide bars 9. Each of the 75 piston rods is also provided with a central enlargement or boss 36 provided with a central orifice 37 in which is mounted a stem 38 on suitable ball bearings, which stem carries a tapered roller 39, which fits into the 80 surrounding groove 15^x of the cam 15.

It will be understood that when the parts are in their neutral position that the cylinder 5 will revolve with the engine fly wheel and that the cylindrical valves 11 to 12² will be carried around the shaft 7 with the revolving casing. During this operation the piston rods 33 will be reciprocated by means of the rollers 39 engaging the inclined groove 15^x, the pistons 31 and 32 moving freely within the cylinders 11 to 11² and 12 to 12².

When, however, the lever arm 21 is moved into the notch 27° as above described and the cylindrical valves 11 to 11² and 12 to 12² carried to their seating position an air cushion will be formed between the piston heads 31 and 32 and the valve seats 11⁶ and 12⁶ preventing longitudinal movement of the piston rods 33. The result of this operation is that the rollers 39 being prevented from longitudinal movement will be locked in the groove 15^x of the cam 15 and will force the shaft 7 to revolve with the cylinder 5.

I will now describe how the shaft 7 is connected to the transmission shaft to drive either directly or in the reverse direction.

40 indicates a clutch sleeve which is mounted upon the shaft 7 and connected thereby by a spline similarly to the sleeve 7¹¹. 40^x indicates a bevel gear which is formed integral with the clutch sleeve 40. 41 indicates a bushing sleeve surrounding the inner portion of the clutch sleeve 40. 42 indicates a sleeve splined to the shaft 7³ similarly to the sleeve 7¹¹ and provided at its inner end with a bevel gear 42^x opposing the bevel gear 40^x. 43 indicates a bushing sleeve surrounding the sleeve 42. Upon the 110 bushing sleeves 41 and 43 are mounted sleeves 44 and 45 provided with annular flanges 46 and 47 which oppose one another and are located to the outside of each of the bevel gears 40^x and 42^x. 48 indicates a cylindrical member secured between the annular flanges 46 and 47 by tap screws 48^x and thereby forming with the annular flanges 46 and 47 a cylindrical housing. 115 48¹ and 48² indicate diametrically located 120

orifices formed in the cylindrical portion 48 and in which are located annular plates 48³ and 48⁴. 49 and 50 indicate cone members. 51 and 52 indicate idler bevel pinions meshing with the gears 40^x and 42^x and provided with cone receiving recesses 49^x and 50^x. 49¹ and 49² indicate ball bearings against which the idler pinions 51 and 52 bear, being held in such position by headed studs 53 and 54. The bevel gear 42^x is provided with a clutch face 42° opposing the clutch face of the member 8. 47° indicates an annular clutch face formed on the outer face of the annular flange 47. The clutch face 47° co-acts with an opposing clutch face 47¹ formed on the outer end of the sleeve 7⁴. 21³ indicates a lug formed on the lever arm 21. 55 indicates a vertical shaft which is journalled in the casting 19. On the upper end of the shaft 55 is secured an arm 55^x and on the lower end an arm 55°. 55¹ indicates a link which has a ball connection 55² to the arm 55^x and a ball connection 55³ to the lug 21³. 56 indicates a rod connected at one end by a ball connection to the arm 55° and at the opposite end by a ball connection 55² to an arm 56 carried on a cross shaft 57 journalled in bearing brackets carried by the side bars 4 and 4^x of the chassis frame. 58 indicates a fork carried by the shaft 57 and engaging the clutch sleeve 40. When the lever 21 is thrown over into the notch 27° as above described the link rod 55¹ is drawn upon so as to swing the arm 55^x in the direction of arrow (see Fig. 2) and the arm 55° in a corresponding direction pulling upon the rod 56, thereby swinging the shaft 57 in the direction of arrow (see Fig. 2) and drawing the clutch sleeve 40 and housing formed by the annular flanges 44 and 45 and cylindrical member 48 in the direction of arrow (see Fig. 5) thereby drawing the clutch faces 42° and 8 into engagement. By this means a direct drive is formed between the shaft 7 and the shaft 7° the sleeve 42 being connected to the shaft 7° by suitable splines 42°. 50 When it is desired to reverse the drive the lever 21 is thrown in the opposite direction so as to engage the notch 27°. By this operation the link rod 55¹ is carried in the opposite direction to arrow (see Fig. 2) and also the rod 56 and cross shaft 57 carrying the clutch sleeve 40 and the gear housing connected thereto in the opposite direction so that the clutch faces 47° and 47¹ are brought into engagement. By the engagement of the clutch faces 47° and 47¹ the gear housing is held in a stationary position. By this means the bevel pinions 51 and 52 are held from rotating in a circular path around the shaft 7. The result is that a drive is formed through the

bevel gear 40^x, bevel pinions 51 and 52 to the bevel gear 42^x and to the shaft 7° driving it in the reverse direction.

It may be found desirable to maintain a pressure of air within the cylinder 5. In order to do this I have provided means which will automatically operate when the engine is running idle.

It will be readily understood that when the engine is running at a maximum speed 75 that the cylinder 5 and shaft 7 will rotate at the same speed and as the engine slows down the relative difference of rate of motion between the cylinder and the shaft increases until a point is reached when the shaft remains stationary and the cylinder 80 revolves around the shaft, that is, when the engine is running idle. When this condition is attained my mechanism for increasing the air pressure within the cylinder is 85 operated. I will now describe this mechanism.

The shaft 7 is provided with a reduced portion 59. 60 indicates a crank arm which is rigidly supported on such reduced portion and when the engine is running idle 90 remains in a stationary position.

61 indicates a piston which operates within the bore 67. 62 indicates a perforated cap which is secured in the upper end of the bore 67. The cap 62 is provided at its upper end with a recess 62^x in which is located a spring 62° bearing at its upper end against the washer 64. 63 indicates a valve stem which extends through the upper end of the cap and is secured by means of a washer 64 and cross pin 65. The upper end of the bore 67 in which the cap 62 is secured is slightly enlarged forming a shoulder 60°. 66 indicates a valve casing provided at its upper 100 end with an annular flange 67 fitting on the shoulder 60°. The lower end of the valve stem 63 is formed into a series of fins 68, which fit the orifice of the valve seat 66, terminating at their lower ends in a valve head 110 69, which fits the tapered seat 70 of the sleeve 66.

When the engine is running idle and the crank 60 is held stationary a reciprocating motion of the piston 61 is produced in the bore 67. As the piston moves inwardly it draws the valve head 69 off its seat against the tension of the spring 62°, drawing air through the perforations of the cap 62 and between the fins into the bore 67. As the piston 61 returns the valve 69 is closed and the air is forced through the passage 61³, lifting the valve 72 off its seat and allowing air to pass through the chamber 61¹ through the passage 61⁴ into the cored chamber 6° and 125 through the orifices 61⁵ into the interior of the cylinder 5.

When, however, the air pressure in the cylinder is sufficient to produce a cushion which will retard the action of the mecha- 130

nism to produce a clutch effect between the cylinder 5 and shaft 7 a back pressure is produced on the valve 72 holding it closed against the upward pressure produced by 5 the piston 61 tending to force the valve 69 and its casing upward against the spring 7²¹ and thereby cutting off any further supply of air to the cylinder 5 until pressure in the cylinder 5 again decreases due to leakage.

10 It will thus be seen when a certain pressure is produced in the cylinder 5, that the valve 72 is held closed against the air pressure produced by the piston 61. When this condition is brought about, the piston 61 and 15 the air pressure that is produced thereby forces the valve 69 and the valve casing 66 upward against the pressure of the spring 7²¹. When the piston 61 moves in the opposite direction the valve casing 66 is reseated 20 by the pressure of the spring 7²¹, that is to say, the valve casing 66 is carried up and down by the compressed air interposed between it and the piston 61. The piston 61 of course recedes until the air pressure is 25 entirely reduced before its return stroke.

From the foregoing description it will be seen that when the operating lever 21 is thrown laterally either to engage the notch 27° or 27' and released so as to enter such 30 notches that the clutch sleeve 26 will be withdrawn, releasing the sleeves 13 and 14 allowing them to move in opposite directions and, therefore, carry the cylindrical valves 11 to 11² and 12 to 12² towards their seating 35 position, gradually choking the passage of air from such cylindrical valves, the air being normally forced therefrom by the reciprocating pistons 31 and 32. As the passage of air is choked producing a vacuum or partial 40 vacuum upon the return stroke of each piston the retarding cushion of air within the cylinders is increased in density and at the opposite end of the mechanism thereby increasing the retarding effect upon the reciprocating piston rods 33, the air cushion opposing one piston and the vacuum producing simultaneously a suction action opposing the movement in the same direction of the other piston of each piston rod 33 and therefore 45 by decreasing the rate of motion of the rollers 39 around the cam 15 until a point is reached when the cylindrical valves are closed, thereby entirely choking off the air and bringing the pistons to a stationary position 50 so that the cam 15 and shaft 7 must revolve with the cylinder 5 and at the same rate of speed.

It will thus be seen from this description 55 that I have devised a device whereby change speed and the reversing may be effected by means of one lever and thereby simplify the operation of handling the car by the driver, decreasing the danger of accident, in which the torque will remain constant during the change of speed, in which any speed desired

may be produced from maximum to zero according to the extent to which the air is choked by the cylindrical valves and the operation of the pistons retarded, the clutching action between the cylinder 5 and shaft 7 being gradually increased by gradual gradation and not by a step-by-step movement and in which all gear stripping will be avoided.

What I claim as my invention is:

1. An automobile change speed control, 75 comprising a rotatable member connected to the engine shaft, reciprocating pistons carried by the rotatable member, a drum shaft, open ended cylindrical valves in which the aforesaid pistons operate, seats carried by 80 the rotatable member and with which the outer open ends of the cylinders coact, means operated by the rotation of the rotatable member for reciprocating the pistons, means for forming a compressed air cushion within 85 the rotatable member such cushion extending into the outer end of the cylindrical valves when unseated, and means for controlling the distance of the cylindrical valves from their seats. 90

2. In an automobile change speed control, the combination with the engine shaft having its speed constant and the driven shaft and control lever, of a cylinder driven from the engine shaft, a cylindrical cam secured 95 to the driven shaft and provided with an inclined surrounding camway, a piston rod slidably carried within the cylinder and a cam roller carried thereby engaging the camway, a piston carried by the piston rod, 100 a cylindrical valve co-acting with the piston, a valve seat co-acting with an end of the cylindrical valve, and means operated by the control lever for adjusting the position of the cylindrical valve in relation to its seat. 105

3. In an automobile change speed control, the combination with the engine shaft having its speed constant and the driven shaft and control lever, of a cylinder driven from the engine shaft, a cylindrical cam secured 110 to the driven shaft and provided with an inclined surrounding camway, a piston rod slidably carried within the cylinder and a cam roller carried thereby engaging the camway, a piston carried at each end of the piston rod, a valve cylinder co-acting with each piston, valve seats carried by the opposing heads of the cylinder and co-acting with the valve cylinders, and means operated by the control lever for similarly adjusting the position of the cylindrical valves in relation to their seats. 115

4. In an automobile change speed control, the combination with the engine shaft and driven shaft, of a cylinder rotatably mounted and driven from the engine shaft, a longitudinally reciprocating piston rod supported in guides within the cylinder, piston heads carried by the piston rod, valve seats carried by the heads of the cylinder, cylin- 120

drical valves co-acting with the seats and in which the pistons operate, resilient means tending to seat the cylindrical valves, a control lever, means operated by the control lever for unseating the cylindrical valves against the compression of the springs, and engaging means between the piston rod and the driven shaft rendered operative by the retarding of the reciprocating movement of the piston rod.

5. In an automobile change speed control, the combination with the engine shaft and the driven shaft and control lever, of a cylinder rotatably mounted concentrically with the driven shaft and driven from the engine shaft, a pair of sleeves mounted upon the driven shaft, resilient means for forcing the sleeves outwardly from each other, a piston rod supported and guided within the cylinder, valve seats carried by the heads of the cylinder, cylindrical valve engaging means between each sleeve and the valve seat at each end of the main cylinder, a piston head carried by the piston rod co-operating with the cylindrical valve at each end of the main cylinder, means operated by the control lever for carrying the sleeves inward against the compression of the springs to unseat the cylindrical valves, and frictional engaging means between the piston rod and driven shaft, the friction of which is adapted to be increased by the retarding of the piston rod.

6. In an automobile change speed control, the combination with the engine shaft and the driven shaft and control lever, of a cylinder rotatably mounted concentrically with the driven shaft and driven from the engine shaft, a pair of sleeves mounted upon the driven shaft, resilient means for forcing the sleeves outwardly from each other, a piston rod supported and guided within the cylinder, valve seats carried by the heads of the cylinder, cylindrical valve engaging means between each sleeve and the valve seat at each end of the main cylinder, a piston head carried by the piston rod co-operating with the cylindrical valve at each end of the main cylinder, means operated by the control lever for carrying the sleeves inward against the compression of the springs to unseat the cylindrical valves, a cylindrical cam carried by the driven shaft having an inclined surrounding endless camway, and a cam-roller carried by the piston rod and engaging the camway.

7. In an automobile change speed control, the combination with the engine shaft and the driven shaft and control lever, of a cylinder rotatably mounted concentrically with the driven shaft and driven from the engine shaft, a pair of sleeves mounted upon the driven shaft, resilient means for forcing the sleeves outwardly from each other, a piston rod supported and guided within the cylinder, valve seats carried by the heads of the

cylinder, cylindrical valve engaging means between each sleeve and the valve seat at each end of the main cylinder, a piston head carried by the piston rod co-operating with the cylindrical valve at each end of the main cylinder, a cylindrical cam carried by the driven shaft having an inclined surrounding endless camway, a cam roller carried by the piston rod and engaging the camway, longitudinally extending rods extending from each sleeve carried by the driven shaft in opposing directions, a lever pivotally mounted centrally of its length and engaging alternately with the rod of each sleeve, a movable member carried by the driven shaft, and means operated by the control lever for forcing such movable member against or from the end of one of the aforesaid sleeves carried by the driven shaft whereby such sleeves are simultaneously carried inward or outward.

8. In an automobile change speed control, the combination with the energy transmitting elements comprising an engine shaft having its speed constant and the driven shaft, and control lever, of a closed cylinder connected to the engine shaft and surrounding the driven shaft, a pneumatic clutch device including opposed cylinders located within the closed cylinder, a pair of pistons coacting with the cylinders and coupled together, such clutch device being adapted to be regulated by the control lever for connecting the aforesaid closed cylinder with the driven shaft, and means for automatically and independently feeding to the interior of the cylinder compressed air for supplying the closed cylinder of the energy transmitting elements whereby an initial resistance of greater pressure than atmosphere opposing the movement of the pistons is provided.

9. In an automobile change speed control, the combination with the engine shaft having its speed constant and the driven shaft and control lever, of a closed cylinder connected to the engine shaft and surrounding the driven shaft, a pneumatic clutch device regulated by the control lever for engaging the revolving cylinder with the driven shaft, means for operating such clutch device from the control lever, an air pump carried in one head of the cylinder, ducts leading therefrom into the interior of the cylinder, and a crank secured to the driven shaft and with which the piston rod of the pump is connected.

10. In an automobile change speed control, the combination with an engine shaft having its speed constant, and the driven shaft and control lever, of a closed cylinder connected to the engine shaft and surrounding the driven shaft, a pneumatic clutch device contained within the cylinder and adapted to seat simultaneously against the opposing

heads of the cylinder and carried to revolve around the driven shaft, pistons incorporated in pairs in the clutch device and adapted to move in unison in the same direction, and
5 coacting frictionally engaging means carried by the pistons and the driven shaft for frictionally engaging such clutch mechanism

with the driven shaft as it revolves there-around.
